UNITED STATES PATENT OFFICE.

EPPA H. RYON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TAKE-UP MECHANISM FOR NARROW-WARE LOOMS.

SPECIFICATION forming part of Letters Patent No. 760,761, dated May 24, 1904.

Application filed December 2, 1903. Serial No. 183,435. (No model.)

To all whom it may concern:

Be it known that I, EPPA H. RYON, a citizen of the United States, residing at Worcester, in the county of Worcester and State of Massachusetts, have invented certain new and useful Improvements in Take-Up Mechanism for Narrow-Ware Looms, of which the following is a specification.

My invention relates to a take-up mechanism for narrow-ware looms or looms for weaving ribbon, tape, &c., and is particularly adapted to be used on double-deck narrow-ware looms to wind the two ribbons or tapes on separate spools arranged one over the other.

The object of my invention is to improve upon the construction of the take-up or winding mechanism of narrow-ware looms as ordinarily made and to provide a take-up or winding mechanism of simple construction in which two ribbons or tapes are wound upon two separate spools simultaneously, one spool being located over the other.

My invention consists in certain novel features of construction of my improvements, as will be hereinafter fully described.

Referring to the drawings, Figure 1 is a front view of a take-up and winding mechanism embodying my improvements looking in the direction of arrow *a*, Fig. 2; and Fig. 2 is a section on line 2 2, Fig. 1, looking in the direction of arrow *b*, same figure.

In the accompanying drawings, 1 represents the loom sides or frames; 2, the breast-beam. The two strands of woven tape or ribbon 3 and 3' pass under the take-up drum 4, fast on the rotary shaft 5, journaled in bearings on the frames 1, and then up between said drum 4 and the roll 6 and over said roll, which bears on the drum 4 and is mounted in the frame 7, which is pivotally supported by studs 7', extending loosely into open-end recesses in the brackets 10, secured upon the under side of the breast-beam 2. (See Fig. 2.) From the roll 6 the tapes 3 and 3' pass over a guide-rod 11 and under a roll 12, fast on a rotary shaft 13. After leaving the roll 12

the two tapes 3 and 3' separate, and one, as 3, passes through a slot near the attached end of a guide-finger 14 and then through a second slot near the free end of said finger 14 onto the rotary spool 15, upon which the tape 3 is wound. The other tape, 3', passes from the roll 12 through a slot near the attached end of guide-finger 14' and then through a second slot near the free end of said finger 14' onto the spool 15', upon which the tape 3' is wound.

The upper rotary spool 15, upon which the tape 3 is wound, is detachably mounted in the ends of a frame 16, provided with hubs pivotally supported on a rod 17, and said spool 15 is located above and is in engagement with the rotary roll 12. The lower rotary spool 15' is detachably mounted in the ends of a frame 16', provided with hubs pivotally supported on the rod 17, and said spool 15' is located below the rotary roll 12 and is held in frictional contact therewith by a spring 18, attached at one end to the frame 16' and at the other end to the frame 16. (See Fig. 2.) The hubs of the pivoted frames 16 and 16' are held in proper position on the rod 17 by collars 19, provided with set-screws 19'.

The upper guide-finger 14, which extends over the upper spool 15, is in this instance attached by a screw 20 to a fork-shaped hub 21, loosely mounted on a rod 22. The lower guide-finger 14', which extends below the lower spool 15', is attached by a screw 20' to a hub 21', loosely mounted on the rod 22. The collars 23, provided with set-screws 23', hold the hubs 21 and 21' in proper position on the rod 22. The tension of the tapes 3 and 3', passing through the slots in the guide-fingers 14 and 14', holds the free ends of the fingers in contact with the spools 15 and 15'.

I will now describe the mechanism for operating my take-up mechanism.

The driven shaft 24 has a pinion 25 fast thereon, (see Fig. 2,) which meshes with and drives a gear 26, mounted on a stud 27 and attached to a pinion 28, which meshes with a gear 29, fast on the shaft 5 of the drum 4.

The drum 4 revolves with said shaft and also a second gear 30, fast on said shaft. The gear 30 meshes with and drives a gear 31, fast on the shaft 13 of the roll 12, and through the 5 rotation of said gear 31 rotary motion is communicated to the shaft 13 and the roll 12. The rotation of the roll 12 communicates rotary motion to the spools 15 and 15', which are in engagement with said roll 12, to wind the 10 tapes 3 and 3' thereon. A pinion 32, fast on the shaft 13, engages a gear 33, loose on a stud 34, and the gear 33 engages a gear 35, loose on a stud 36 and connected with a cam 37, having a cam-groove 37' therein. In the groove 15 37' of the cam 37 a roll 38' on a lever 38 extends and travels. The lever 38 is centrally pivoted at 39 on a stand 40' and is connected by a link 41 with a hub 42, fast on the rod 22, which has a longitudinal reciprocating motion. The revolution of the driven shaft 24, through pinion 25, gear 26, pinion 28, gear 29, gear 30, and gear 31, communicates rotary motion to the roll 12 and through said roll to the wind-up spools 15 and 15', and at 20 25 the same time, through pinion 32, gear 33, gear 35, cam 37, lever 38, link 41, and hub 42, a longitudinal reciprocating motion is communicated to the rod 22, carrying the guide-fingers 14 and 14', to cause said fingers to have 30 a traverse or reciprocating motion to guide the tapes 3 and 3' onto the spools 15 and 15'.

I have only shown in the drawings one set of spools 15 and 15' and guide-fingers 14 and 14'; but it will be understood that there will 35 be a series of them extending across the loom, and the rotary movement of all of the spools and the transverse movement of all of the guide-fingers will be governed by the gearing and the worm mechanism above described and 40 shown in the drawings.

It will be understood that the details of construction of my improvements may be varied, if desired.

Having thus described my invention, what 45 I claim as new, and desire to secure by Letters Patent, is—

1. In a take-up mechanism for narrow-ware looms, the combination of a rotary shaft, a roll fast thereon, a rod, two oppositely-extending frames pivotally mounted on said rod, a winding-spool carried by each of said oppositely-extending frames and having peripheral driving bearing on opposite portions of said roll, and traverse means operating simulta-

neously with said spools for laying the fabric 55 thereon.

2. In a take-up mechanism for narrow-ware looms the combination of a rotary shaft, a roll fast thereon, a rod, two oppositely-extending frames pivotally mounted on said rod, a winding-spool carried by each of said oppositely-extending frames and having peripheral driving bearing on opposite portions of said roll, a spring connecting the spool-carrying frames, and traverse means operating simultaneously with said spools for laying the fabric 65 thereon.

3. In a take-up mechanism for narrow-ware looms, the combination of a rotary shaft, a roll fast thereon, two rods disposed adjacent 70 to said shaft, two oppositely-extending frames pivotally mounted on one of said rods and carrying winding-spools disposed on opposite sides of said roll, guide-fingers mounted on the other of said rods and disposed to deliver fabric 75 to said spools, and means for imparting a traverse motion to said guide-fingers to lay the fabric spirally on the spools.

4. In a take-up mechanism of a narrow-ware loom, the combination with a take-up drum, 80 a rod, two frames pivotally mounted thereon and two winding-spools carried thereby, arranged one over and in line with the other, and an intermediate rotary roll over which the two woven tapes pass prior to being wound 85 on the spools, said rotary roll being also in frictional engagement with the two winding-spools, and two guide-fingers, one for each tape, and in contact with the winding-spools, and means for communicating a traverse or reciprocating motion to said guide-fingers, of means 90 for operating said drum, rotary roll, and guide-fingers, comprising a driven pinion, meshing with and driving a gear on a take-up-drum shaft, and a second gear on said take-up-drum shaft, meshing with and driving a gear fast on the shaft of the rotary roll, a pinion fast on said shaft meshing with and driving a gear loose on a stud, and said gear meshing with and driving a gear loose on a shaft, and connected with a cam which operates the guide-fingers, through intermediate mechanism, substantially as shown and described.

EPPA H. RYON.
